CLAIM

The ornamental design for a housing for electronic components, as shown and described.

DESCRIPTION

FIG. 1 is an isometric view of the top, left side, and front side of a housing for electronic components showing a first embodiment of the design.

FIG. 2 is a rear elevational view of the housing for electronic components of FIG. 1.

FIG. 3 is a front elevational view of the housing for electronic components of FIG. 1.

FIG. 4 is a left side elevational view of the housing for electronic components of FIG. 1.

FIG. 5 is a right side elevational view of the housing for electronic components of FIG. 1.

FIG. 6 is a top plan view of the housing for electronic components of FIG. 1.

FIG. 7 is a bottom plan view of the housing for electronic components of FIG. 1.

FIG. 8 is an isometric view of the top, left side, and front side of a housing for electronic components showing a second embodiment of the design.

FIG. 9 is a rear elevational view of the housing for electronic components of FIG. 8.

FIG. 10 is a front elevational view of the housing for electronic components of FIG. 8.

FIG. 11 is a left side elevational view of the housing for electronic components of FIG. 8.

FIG. 12 is a right side elevational view of the housing for electronic components of FIG. 8.

FIG. 13 is a top plan view of the housing for electronic components of FIG. 8; and,

FIG. 14 is a bottom plan view of the housing for electronic components of FIG. 8.

(Continued)

The evenly-spaced broken lines in the figures form no part of the claimed design. The dot-dash broken lines in the figures define areas that form no part of the claimed design.
